FIG. 8.

Inventor

ALEXANDER DJIDICS,

By *Samuel Henick*,
Attorney

UNITED STATES PATENT OFFICE.

ALEXANDER DJIDICS, OF TAMAQUA, PENNSYLVANIA, ASSIGNOR TO ATLAS POWDER COMPANY, OF WILMINGTON, DELAWARE, A CORPORATION OF DELAWARE.

DEVICE FOR FIRING EXPLOSIVES BY ELECTRICITY.

Application filed November 21, 1924. Serial No. 751,281.

To all whom it may concern:

Be it known that ALEXANDER DJIDICS, citizen of the United States, residing at Tamaqua, in the county of Schuylkill and

5 State of Pennsylvania, has invented certain new and useful Improvements in Devices for Firing Explosives by Electricity, of which the following is a specification.

This invention relates to a device for firing explosives by electricity and it has for its object to provide an improved device of the character of those commonly known as electrically fired matches. The device of the present invention is adapted to be used 10 as a general purpose igniting device for explosives either with or without a detonator.

It is a primary object of the invention to provide a device of the character indicated, characterized by extreme simplicity in construction and consequent economy in manufacture.

Further objects and advantages of the invention will be set forth in the detailed description which follows:

25 In the accompanying drawings:

Figure 1 is a side elevation of the match of the present invention with the match composition at the lower end thereof shown partly in section and partly in elevation.

30 Figure 2 is an end view of the match.

Figure 3 is a plan view of the body portion of the match with the current carrying wires omitted.

35 Figure 4 is a sectional view upon line 4—4 of Figure 1.

Figure 5 is a detail view of the insulating base hereinafter described.

40 Figure 6 is a view substantially like Figure 1 illustrating a modified form of the invention.

Figure 7 is a plan view of the structure illustrated in Figure 6 with the current carrying wires omitted, and

45 Figure 8 is a sectional view upon line 8—8 of Figure 6.

Like numerals designate corresponding parts in all of the figures of the drawing.

50 Referring to Figures 1 to 5, and particularly to Figure 5, the numeral 5 designates a base plate of insulating material which may be made of fiber, heavy paper or the like. Metal terminal plates 6 and 7 are clipped about the outer edges of the base 5, as illustrated in Figure 3, and, in addi-

tion, their inner edges are crimped inwardly as indicated at 8, about the edges of the central opening 9 that is formed in the base 5. Thus these metal terminal plates are firmly bound to the base 5 but are held in spaced and insulated relation to each other. The current carrying, lead wires, 10 and 11 are soldered or otherwise secured to the respective plates 6 and 7. The lower edges of the terminal plates are beveled or cut away as indicated at 12 to leave a space between them, which space is spanned by a bridge wire 13 of platinum, or any other suitable metal or alloy of metals. The lower edges of the terminal plates are preferably notched out as indicated at 14 for the reception of the bridge wire. The space between the cut away lower ends of the terminal plates is filled with a match composition, as indicated at 15, in which the bridge wire is embedded.

When current is supplied to the match in the usual and well known way, the bridge wire becomes incandescent and ignites the match composition and this in turn sets off any explosive with which the match may be associated.

In the form of the invention illustrated in Figures 6 to 8, the structure is very similar to that illustrated in Figures 1 to 5. A base 5^a like that illustrated in Figure 5, is employed and the terminal plates 6^a, 7^a are clipped about the edges of the base 5 as illustrated in Figure 7. In addition, portions of their inner edges are bent inwardly into engagement with the opposite edges of the central opening 9^a of the base 5^a in much the manner described with respect to Figure 1. Substantially the only difference between the structures of Figures 1 and 6 is in the shape of the terminal plates and the extent to which they overlap the base.

It is to be understood that the invention is not limited to the precise construction set forth but that it includes within its purview whatever changes fairly come within either the terms or the spirit of the appended claims.

Having described my invention, what I claim is:

1. An electrically fired match comprising a base of insulating material having an opening formed therethrough and a pair of terminal plates, the outer edges of which

are engaged about the outer edges of the base and the inner edges of which are engaged with the edges of said openings.

2. An electrically fired match comprising
5 a flat plate of insulating material constituting a base, a pair of metallic plates, the outer edges of which are engaged about the outer edges of the base and the inner edges of which are engaged with the edges of an
10 opening formed through said base.

3. A structure as recited in claim 3, in combination with a bridge wire spanning the space at the lower ends of said terminal plates and a body of match composition in which said wire is embedded.

4. A structure as recited in claim 3, in combination with a bridge wire extending

between the lower ends of said plates and connected thereto.

5. A structure as recited in claim 3, 20 wherein the lower ends of said plates are cut away at an angle to space their outer lower corners a material distance from each other, a bridge wire connected to the lower outer corners of said plates, and a body of 25 match composition in which said bridge wire is embedded.

In testimony whereof he affixes his signature in the presence of two witnesses.

ALEXANDER DJIDICS.
